LAVATORY

Donald C. Schrock, La Grange, and Richard J. Contant, Chicago, Ill., assignors to Crane Co., Chicago, Ill.,
a corporation of Illinois

Filed May 21, 1969, Ser. No. 17,254

Term of patent 14 years

Int. Cl. D23—02

U.S. Cl. D23—58

FIG. 1

FIG. 1 is a perspective view of the lavatory showing our new design;

FIG. 2 is a plan view thereof;

FIG. 3 is a side elevation thereof.

The rear of the lavatory is of conventional configuration. The bottom of the lavatory is plain and generally follows the profile of the top which is best seen in FIG. 1.

We claim:

The ornamental design for a lavatory, as shown and described.
